UNITED STATES PATENT OFFICE.

HENRY E. CHAPMAN, OF ALBANY, NEW YORK.

IMPROVEMENT IN PILL-MACHINES.

Specification forming part of Letters Patent No. 14,904, dated May 20, 1856.

To all whom it may concern:

Be it known that I, HENRY E. CHAPMAN, of the city and county of Albany, and State of New York, have invented a new and useful Machine for Making Pills; and I do hereby declare the following to be a full, clear, and exact description of the construction and operation of the same, reference being had to the annexed drawings, making a part of this specification, in which—

Figure 1 is a longitudinal section; Fig. 2, a plan, and Fig. 3 a transverse section at $x x$, in which—

A is the frame; B B, two revolving cylinders, of different diameters, having semicircular grooves corresponding with each other turned in their peripheries; C, feeding-cylinder, having a nose-piece perforated to correspond with the grooves in the cylinders B B; D D, cog-wheels between cylinders B B; E E, driving-wheel and pinion; F, bell-crank lever for feed-gear; G, pawl; H, ratchet-wheel; I, feed-screw; J, piston or follower to feeding-cylinder; K, knife; L, driving-shaft, on which are two pins, $l l'$, for forcing down the knife; M, driving-crank; N, bed-piece, having a grooved face to correspond with grooves in cylinders B B, and which is fitted closely to the smaller cylinder, having its face toward and curved to the radius of the larger cylinder; O O, springs for raising the knife; P P, guides for the knife.

In operating the machine the feeding-cylinder is filled with the pill composition. When motion is given to the driving-shaft L, the composition is forced through the perfo-

rations of the nose-piece of the feeding-cylinder by means of the bell-crank lever F, pawl G, ratchet-wheel H, feed-screw I, the follower J, and their attachments. When a sufficient quantity has been forced through, the knife K is forced down by the pins $l l'$ striking it on the top, which, as it passes the perforations, cuts off small cylindrical pieces of the composition, which fall into the grooves of the cylinders B B, whose surfaces, being driven at different rates of speed by means of the cog-wheels D, give to the pills a rolling motion and shape them into aspherical form, the bed-piece N serving the purpose of retaining the rolling motion of the pills and smoothing down any remaining inequalities after they have passed from between the cylinders. After the knife K has made its cut, and the pins $l l'$ have passed from their point of contact with it, it is carried up to its place by means of the springs O O.

Having thus described the construction and operation of my machine, what I claim as my invention, and desire to secure by Letters Patent, is—

The feeding-cylinder C, the knife K, the grooved bed-piece N, and the two grooved cylinders B B, having their surfaces driven at different rates of speed, all substantially as herein described, and for the purposes set forth.

HENRY E. CHAPMAN.
